UNITED STATES PATENT OFFICE

BENSON STORFER, OF BROOKLYN, NEW YORK, ASSIGNOR TO STORFER LABORATORIES, INC., OF NEW YORK, N. Y., A CORPORATION OF NEW YORK

DESIGN FOR A PERFUME BOTTLE OR SIMILAR ARTICLE

Application filed November 21, 1929. Serial No. 33,514. Term of patent 3½ years.

To all whom it may concern:

Be it known that BENSON STORFER, a citizen of the United States, and resident of Brooklyn, New York, in the county of Kings and State of New York, has invented a new, original, and ornamental Design for a Perfume Bottle or Similar Article, of which the following is a specification, reference being had to the accompanying drawing, forming part thereof, in which the figure is a perspective view of the design embodying my invention.

I claim:

The ornamental design for a perfume bottle or similar article, substantially as shown.

Dated, New York city, November 14, 1929.

BENSON STORFER.
